United States Patent

Des. 240,665

Patented July 20, 1976

240,665

SOUND PROJECTOR

Jochen Kramer, Wolfburg, Claus Prochnow, Braunschweig, and Reinhard Sobotta, Mascherode, Germany, assignors to Rollei-Werke Franke & Heidecke, Braunschweig, Germany

Filed Jan. 17, 1975, Ser. No. 541,930

Claims priority, application Germany July 25, 1974

Term of patent 14 years

Int. Cl. D16—02

U.S. Cl. D16—21

FIG. 1

FIG. 2

FIG. 3

FIG. 4

FIG. 5

FIG. 1 is a top plan view of a sound projector, showing our new design;

FIG. 2 is a front elevational view thereof;

FIG. 3 is a rear elevational view thereof;

FIG. 4 is a right side elevational view thereof; and

FIG. 5 is a left side elevational view thereof.

The bottom of the projector is substantially plain and unornamented.

We claim:

The ornamental design for a sound projector, substantially as shown and described.
